UNITED STATES PATENT OFFICE.

HARRY I. MAURER, OF BETHLEHEM, PENNSYLVANIA.

MILK-BOTTLE HOLDER.

1,412,128.

Specification of Letters Patent. Patented Apr. 11, 1922.

Application filed June 10, 1921. Serial No. 476,411.

To all whom it may concern:

Be it known that I, HARRY I. MAURER, a citizen of the United States, residing at Bethlehem, in the county of Northampton and State of Pennsylvania, have invented 5 new and useful Improvements in a Milk-Bottle Holder, of which the following is a specification.

My invention relates to new and useful 10 improvements in a milk bottle holder, and has for its object to provide an exceedingly simple and effective device of this character which will be relatively inexpensive in the cost of manufacture and light in weight although strong and durable.

Another object of the invention is to provide a milk bottle in an upright position when filled and which may be inserted in the holder in an inverted position when 20 empty so as to permit the bottle to drain after the same has been washed and which will also indicate whether or not a customer has been served and also whether or not the milkman has passed.

25 A further object of the invention is to provide a milk bottle holder consisting of an upper ring of one diameter and a lower ring of a smaller diameter, the said rings being joined together by angular strips to produce 30 the completed holder one of said angular strips having an extension which with its body produces a clip for holding sheets of paper containing orders, while another of said strips has holes through its body portion 35 for the passage of suitable attaching devices whereby the holder may be fastened to a suitable support.

With these ends in view, this invention 40 consists in the details of construction and combination of elements hereinafter set forth and then specifically designated by the claim.

In order that those skilled in the art to 45 which this invention appertains, may understand how to make and use the same, I will describe its construction in detail, referring by numerals to the accompanying drawings forming a part of this application, in which:—

50 Fig. 1, is a side elevation of a milk bottle holder made in accordance with my improvement, showing it attached to a support

and having a bottle therein in an upright position.

Fig. 2, is a similar view with the holder 55 removed from the support and having a bottle in an inverted position therein.

Fig. 3, is a plan view thereof with the bottle removed.

Fig. 4, is a side elevation thereof. 60

In carrying out my invention as here embodied, I provide an upper ring 2 preferably of wire to which are fixed the upper ends of the body portions 3 of the angular strips 4 by folding said upper ends about the wire ring and crimping it or otherwise securely fastening the same in place, while the inner ends of the arms 5 of said angle strips are singularly fixed to another ring 6 of smaller diameter than the ring 2 and which is also preferably formed of wire, said ring leaving an open space of sufficient size for the passage of the mouth and neck of the milk bottle 7 when in an inverted position, 70 as shown in Fig. 2 the shoulder or flared portion of the neck engaging the smaller ring 6 as will be obvious and when the milk bottle is in its inverted position any water which may have remained in the bottle after washing will drain therefrom prior to the time 75 of collection.

The ring 6 although being larger than the mouth and a portion of the neck of the milk bottle is smaller than the bottom of the same bottle and with the arms 5 of the angle strips 4 form the bottom of the container on which the milk bottle rests when in an upright position as shown in Fig. 1 and being in an upright position will indicate to the customer that the morning's milk has been 90 served. In order that the holder may be secured to a suitable support 8 such as a post or fence at a height to prevent cats, dogs or other animals coming in contact with or breaking the bottles a number of holes 9 95 are formed in one end of the body portion of one of the angle strips for the passage of suitable fastening devices 10 such as nails or their equivalent.

In order that a piece of paper, book or 100 other article having directions, orders or other information thereon may be attached to the holder and prevented from being blown away and lost the upper end of the

body of one of the angle strips, preferably the front one, is provided with an extension 11 bent upon itself which coacts with the body of the strip to produce a clip the action 5 of which is obvious.

From the foregoing description it will be seen that I have produced a milk bottle holder that may be manufactured at a relatively small expense and which may be 10 readily cleansed so that it will be sanitary and when in use the milk bottle will be held in the desired position according to whether it is filled or empty and as there are no locks or working parts to get out of order 15 it is practically indestructible and a bottle either in an upright or inverted position may be readily and quickly removed therefrom.

It is to be understood that in place of the 20 rings similar members of other shapes might be utilized and it is possible that a number of these holders could be attached to each other or made as a single device where more than one bottle of milk is delivered at 25 a time. This device when in use makes it unnecessary to stoop when delivering or collecting the bottles as the holder may be located at a suitable height and as the bottles

are always partially surrounded they cannot fall from the holder and the likelihood 30 of breaking the bottles is reduced to a minimum.

Of course I do not wish to be limited to the exact details of construction as herein shown as these may be varied within the 35 limits of the appended claim without departing from the spirit of my invention.

Having thus fully described my invention, what I claim as new and useful is:

A milk bottle holder comprising an upper 40 ring, a lower ring of smaller diameter, a plurality of angular strips each consisting of a body and an arm at right angles to said body, said strips being disposed about the rings in spaced relation with the upper ends 45 of the bodies of said strips fixed to the upper ring and the inner ends of the aforementioned arms fixed to the lower smaller ring and an extension formed with the upper 50 end of the body of one of said strips and bent upon said body so as to coact therewith and produce a clip.

In testimony whereof, I have hereunto affixed my signature.

HARRY I. MAURER
